UNITED STATES PATENT OFFICE.

HORACE MANDERS, OF LONDON, ENGLAND.

APPARATUS FOR THE PRODUCTION OF CONTINUOUS ELECTRICAL OSCILLATIONS.

1,105,984.

Specification of Letters Patent.

Patented Aug. 4, 1914.

Application filed October 30, 1909. Serial No. 525,451.

To all whom it may concern:

Be it known that I, HORACE MANDERS, a subject of the King of Great Britain, of London, England, have invented certain new and useful Improvements in Apparatus for the Production of Continuous Electrical Oscillations, of which the following is a specification.

This invention relates to improvements in and relating to apparatus for the production of continuous electrical oscillations, and to the application of the same.

I have previously (in the specification of British Patent No. 5164 A. D. 1907) described a method and means of producing oscillatory currents of electricity from continuous currents of the same, in which the principal feature is that the cathode of the oscillator is composed of aluminium, or of some metal of relatively low atomic weight; whereas the anode must be composed of a metal of higher atomic weight than that of the cathode.

I have found that in the production of continuous electrical oscillations remarkable results as regards the regularity, continuity and duration of the oscillating arc can be obtained by using a pair of condenser electrodes of a special form, namely, that of a block having a flattened discharge area at and near the axis, whereas the portion outside this area is thrown back or beveled off.

The present invention consists in the use of such block electrodes for the production of continuous electrical oscillations.

The invention further consists in the employment of a modified form of such block condenser electrodes, wherein the flat central discharge portion is raised as a nipple above a rounded mammary shaped base.

The invention further consists in the application to the chamfered or thrown back faces of such block condenser electrodes of insulating material for the purpose of increasing the dielectric effect between the chamfered or thrown back parts of the pair of block electrodes.

In the accompanying drawings: Figure 1 represents in plan and elevation a form of my block electrode. Fig. 2 is an elevation showing the application of insulation to the beveled off portion. Fig. 3 is a view of a pair of electrodes with insulation similarly applied. Fig. 4 is an elevation of a modified form of the block electrode in which the

peripheral non-discharge portion is thrown back in a more pronounced way from the central portion, giving a block electrode of mammary form. Fig. 5 illustrates an electrode like that shown in Fig. 4, with a dielectric applied to the thrown back portion. Fig. 6 illustrates the electrodes applied to a closed interrupter.

I prefer to make the block electrodes from metal rod of large diameter, but, as rod of 65 larger diameter than 1 inch is generally unobtainable, for larger sizes special castings may be made. Ordinarily, I cut off a length of an inch and a half, more or less, from rod of one inch, more or less, in diameter; in 70 the center of one end I sink a female screw to take a conducting rod, which also serves as a support to the electrode. The opposite end of this block is turned or filed and emery papered until it is quite smooth and 75 plane. Then, from the center, I draw a circle, the rim of which is about an eighth of an inch, more or less, from the circumference of the block (A, Fig. 1). The part contained within the said circle is the surface or area of discharge; the part which lies outside, between the circle and the circumference of the block, I bevel off, or chamfer, (B, Fig. 1). When completed, 80 these electrodes present the appearance of a 85 flattened hemisphere surmounting a cylinder. When the circular, flat, plane surfaces of two such electrodes are placed opposite to one another so as to articulate and form an arc-gap, and the circuit is closed, an oscillatory condenser discharge takes place between them. The remainder of the opposing surfaces of conducting material, being chamfered and so thrown back from each other, 90 offer a greater thickness of dielectric between 95 the two armatures; hence, the discharge is confined to the desired area within the inner circle. When used with high voltages, I prefer to strengthen the dielectric by filling up the chamfered area of the armatures 100 with a suitable insulating material C. I find that for voltages up to 200, or a little more, the preparation of kaolin, sold under the name of "Fortafix" or "Cementium", is very efficient for the purpose; but for 105 higher voltages, I find it best to use either steatite, papier-mâché, ordinary court plaster, or superimposed layers of thin silk. These layers of silk are so disposed that the central holes gradually increase in diameter. 110

ter as each recedes from the discharge area; so that, in section, the insulating material of a single electrode gives the appearance of a centrally hollow plano-concave lens, Fig. 2, and when two such electrodes are placed opposite to each other in the arc-gap, the appearance of the inter-articulating insulating substance is that of a centrally hollow bi-concave lens, Fig. 3.

10 Another plan of making these electrodes, which accomplishes the same purpose, is to cut away a portion D of the circumference of the block, after leveling as before, about an eighth of an inch, or more, toward the center, according to the diameter of the block, and at least a sixteenth of an inch, or more, in depth; the edge of the elevated circle is slightly chamfered, but the shoulder is chamfered as already described, until 15 the block presents a breast and nipple or mammary appearance, Fig. 4. The chamfered shoulder may be treated with appropriate insulating material (Fig. 5) as already described, but not necessarily to the 20 level of the summit of the nipple.

These condenser electrodes may be used in the arc-gap as pairs of a similar kind; or one of the pair may be of the flattened hemispherical kind first described, and the 25 other, of the same pair, of the mammary shape.

The electrodes are shown at e' and e'', Fig. 6, applied to a known type of interrupter.

30 I have also discovered that when the condenser electrodes, above described, are used, there are certain exceptions to the general rule of the electrical functional relations of anode and cathode promulgated in my British Patent No. 5164 A. D. 1907. I have ascertained that, with my condenser electrodes as above, I can obtain excellent oscillations when aluminium is opposed to aluminium; also iron to iron; and zinc to zinc (especially 35 in the latter case when the anode is of the mammary form), that when iron and zinc are opposed to each other within the arc-gap the oscillations are equally good whichever metal is used as anode or cathode, respectively, to the other. Hence any of these 40 four combinations of metals may be used to obtain continuously maintained electrical oscillations from an ordinary alternating current. I have also ascertained that, with 45 my condenser block electrodes, as above, when iron, especially in the form of steel, as anode, is opposed to cadmium as cathode, excellent oscillations are obtained, which are best when the discharging surface of the 50 anode electrode is of less area (as in the mammary form) than that of the cathode; that when cobalt as anode is opposed to zinc as cathode, very powerful and steady oscillations are produced, more especially 55 when the anode is of the mammary form.

I have ascertained that many advantages result when the oscillating arc discharge is caused to take place in compressed air or in an atmosphere of nitrogen or carbon dioxide, especially when such atmosphere is under a pressure of one or more atmospheres, and I have found that the results are particularly advantageous when the contained air or gas is kept dry in the chamber and the products of combustion are absorbed by soda lime or the like. Fig. 6 represents a suitable apparatus for attaining the purpose. Such apparatus comprises an arc gap chamber a which may consist of a glass vessel b the rim of which fits into a groove c in the under surface of a lid d made of an insulating material, such as vulcanite. e¹ e² are the block electrodes attached to rods f g of conducting material, the former of which passes down through a stuffing box h on the lid and can be adjusted by a micrometer screw i. j¹ is the terminal attached to the bent rod g of the lower electrode and j² is the other terminal, in flexible connection by a wire k with the rod f. l is a valve for admitting the air or gas to the chamber a, and m represents a manometer for indicating the pressures in the chamber. n is a stop cock for allowing the air or gas to escape. o is a base board to which the lid is clamped by rods p and butterfly nuts q' so that the chamber becomes hermetically sealed when the parts are clamped together, the groove c being lined with rubber or elastic material with this object. Any other suitable means may be employed to provide for hermetic sealing of the chamber.

I may construct the body of the arc gap chamber of metal. In this case the rod for carrying the lower electrode may project up from the center of the bottom of the chamber. If desired the conducting rods that carry the electrodes may be disposed horizontally. Soda lime or like absorbent material may be placed in the chamber for the purpose above mentioned.

What I claim and desire to secure by Letters Patent is:—

1. In apparatus for the production of continuous electrical oscillations, a pair of electrodes of block form, each having a flattened discharge area at and near the axis, and having the portion outside this area at the discharge side thrown back, substantially as described.

2. In apparatus for the production of continuous electrical oscillations, an electrode of block form having a flattened discharge area at and near the axis and having the portion outside this area at the discharge side thrown back and having an insulating material applied to said thrown back portion.

3. In apparatus for the production of continuous electrical oscillations, a pair of elec-

trodes of block form, each having a flattened discharge area at and near the axis and having the portion outside this area at the discharge side thrown back, the anode of said 5 pair consisting of iron and the cathode of cadmium.

4. In apparatus for the production of continuous electrical oscillations, a pair of electrodes of block form each having a flattened 10 discharge area at and near the axis and having the portion outside this area at the discharge side thrown back, in combination with insulating material applied in between the said thrown back portion.

15 5. In apparatus for the production of continuous electrical oscillations, a pair of electrodes of block form, each having a flattened discharge area at and near the axis and having the portion outside this area at the 20 discharge side thrown back, the flattened discharge area being upon a nipple-like portion

projecting from the body of the block, substantially as described.

6. In apparatus for the production of continuous electrical oscillations, a pair of electrodes of block form, each having a flattened 25 discharge area at and near the axis and having the portion outside this area at the discharge side thrown back, the flattened discharge area being upon a nipple-like portion 30 projecting from the body of the block in combination with insulating material applied between the thrown back portions of the electrodes, substantially as described.

In witness whereof, I have hereunto 35 signed my name in the presence of two subscribing witnesses.

HORACE MANDERS.
